UNITED STATES PATENT OFFICE.

JOHN J. REGAN, OF JERSEY CITY, NEW JERSEY.

LOCOMOTIVE-BOILER.

SPECIFICATION forming part of Letters Patent No. 690,182, dated December 31, 1901.

Application filed June 6, 1901. Serial No. 63,377. (No model.)

To all whom it may concern:

Be it known that I, JOHN J. REGAN, a citizen of the United States, and a resident of Jersey City, in the county of Hudson and State of New Jersey, have invented a new and Improved Locomotive-Boiler, of which the following is a full, clear, and exact description.

The object of the invention is to provide a new and improved locomotive-boiler which is simple and durable in construction and arranged to provide a large heating-surface and to insure complete combustion of the fuel, so that the boiler can be run with the greatest economy in the consumption of fuel and without danger of early destruction of the parts of the boiler.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a longitudinal sectional elevation of the improvement. Fig. 2 is an end view of the same. Fig. 3 is a transverse section of the same on the line 3 3 in Fig. 1, and Fig. 4 is a similar view of the same on the line 4 4 in Fig. 1.

The improved locomotive-boiler consists, essentially, of an external shell A and an internal shell B, arranged eccentrically in the external shell and forming with the same a steam and water compartment C, leading to a steam-dome D, from which extends the usual supply-pipe E for carrying the generated steam to the engine. The internal shell B consists of a fire-box F, a first set of smoke-flues G extending through a water-compartment H, next to which is arranged an auxiliary combustion-chamber I, containing water-jacketed or fire-brick deflectors J J', and the forward end of the shell B is occupied by a second set of smoke-flues K, extending through a water-chamber L. The chambers H and L are connected by openings H' and L' with the steam and water compartment C, so that water freely circulates through said chambers around the flues G and K. The deflectors J J' are similarly connected by openings

J² with the steam and water compartment C, so that water circulates in said water-jacketed deflectors and prevents the same from 55 rapid destruction by the heat and gases passing through the auxiliary combustion-chamber I. In the bottom of the latter is arranged an air-inlet I', extending through the steam and water compartment C and the shell A to 60 the outside, and in this inlet I' is preferably arranged a valve under the control of the engineer to admit air to the chamber I, and thereby insure complete combustion therein of the smoke and gases passing through the 65 same from the set of flues G to the set of flues K. The forward end B' of the internal shell B, containing the fire-box F, is preferably corrugated transversely, as is plainly illustrated in Fig. 1, so as to give the desired rigidity to the fire-box and allow the same to 70 readily expand and contract when the boiler is in use.

In the fire-box F is arranged a grate F', extending forwardly and downwardly, and below the grate is an ash-pit F². Access is had to the fire-box and ash-pit through a fire-door F³ and an ash-pit door F⁴. An air-inlet P is also arranged in the bottom of the ash-pit F², near the rear end thereof, and this air-inlet is similar to the air-inlet I' and is likewise under the control of the engineer to admit more or less air to the ash-pit and the burning fuel on the grate F', and thereby aid combustion. The bottom portion of the chamber H is filled in with fire-brick H², so as to 85 form a bridge-wall.

The forward end of the internal shell B terminates a distance from the forward end of the external shell A, and as the steam and water compartment C is closed at the end of the shell B by a suitable sheet C' it is evident that a smoke-box N is formed in the front end of the shell A and leads to a smoke-stack O.

When the fire-box is in use, the smoke and gases arising from the burning fuel on the grate F' in the fire-box F pass through the flues G into the chamber I and are deflected therein in a downward direction by the water-jacketed deflector J and then rise in the chamber I over the water-jacketed deflector J' to reach the flues K, and the smoke and gases while in the chamber I are subjected to

an auxiliary combustion by the introduction of air through the inlet-opening I', so that complete combustion of the fuel takes place. As the water circulates in the chambers H 5 and L and around the chamber I and in the water-jacketed deflectors J J', it is evident that a very quick generation of steam takes place without loss of fuel, so that the greatest economy in the consumption of fuel is obtained with an extremely rapid generation of steam.

Having thus fully described my invention, I claim as new and desire to secure by Letters Patent—

- 15 1. A steam-boiler comprising an external shell, an internal shell disposed longitudinally within said external shell, eccentrically thereto, and forming a water and steam compartment which surrounds said internal shell, the last-named shell being divided into a primary combustion-chamber, an auxiliary combustion-chamber, and other chambers which are equipped with independent sets of smoke-flues.
- 25 2. A steam-boiler comprising an external shell, an internal shell disposed longitudinally and eccentrically therein, said shells forming a water and steam chamber which surrounds the inner shell, and said inner shell divided into a primary combustion-chamber, an auxiliary combustion-chamber, and other water-circulating chambers which are cut off from communication with said combustion-chambers and are in communication with said surrounding chambers, and spaced sets of smoke-flues disposed in said water-circulating chambers and communicating with the auxiliary combustion-chamber.
- 35 3. A boiler, comprising an external shell,

an internal shell arranged eccentrically there-in and forming therewith an intermediate steam and water chamber, said internal shell containing a fire-box, a plurality of spaced sets of smoke-flues, and an auxiliary combustion-chamber between the spaced sets of flues, 40 45 as set forth.

4. A boiler, comprising an external shell, an internal shell arranged eccentrically there-in and forming with the latter a steam and water compartment, the latter as well as the 50 forward end of said internal shell terminating a distance from the front end of the external shell to form a smoke-box, said shell containing a fire-box, a plurality of spaced flues, and an auxiliary combustion-chamber 55 between the sets of spaced flues, as set forth.

5. A steam-boiler, comprising a primary combustion-chamber, water-chambers spaced relatively to one another, an auxiliary combustion-chamber disposed between said wa- 60 ter-chambers, a steam and water chamber surrounding the said combustion and water chambers and having circulating communication with the water-chambers, spaced sets of smoke-flues disposed within the water-cham- 65 bers and communicating with one or both com-bustion-chambers, and jacketed deflectors in communication with the water and steam chamber and extending into the auxiliary combustion-chamber.

In testimony whereof I have signed my name to this specification in the presence of two subscribing witnesses.

JOHN J. REGAN.
